N. GIACOMELLI.

RAIL CHAIR.

APPLICATION FILED MAR. 15, 1920.

Patented Aug. 3, 1920.

Inventor

Nazzareno Giacomelli

By *William Clinton*

Attorney

UNITED STATES PATENT OFFICE.

NAZZARENO GIACOMELLI, OF NEWBURGH, NEW YORK.

RAIL-CHAIR.

1,348,794.

Specification of Letters Patent.

Patented Aug. 3, 1920.

Application filed March 15, 1920. Serial No. 365,967.

To all whom it may concern:

Be it known that I, NAZZARENO GIACOMELLI, a subject of the King of Great Britain, residing at Newburgh, in the State of New York, United States of America, have invented certain new and useful Improvements in Rail-Chairs; and I do hereby declare that the following is a full, clear, and exact description of the invention, such as will enable other skilled in the art to which it appertains to make and use the same.

The present invention has relation to rail chairs for railway rails and the principal object is to provide a device, adapted for cushioning the rails and for equalizing the stress encountered thereby.

Another object of the invention is to provide a device by the use of which the ordinary tie joining attachments are dispensed with.

A further object is to provide a device by the use of which the life of the rail tie is prolonged.

With the above and other objects in view which will hereinafter appear as the description continues, the invention consists of the novel features of construction, combination and formation of parts as will be hereinafter more fully described and particularly pointed out in the appended claims.

In the accompanying drawings has been shown a simple and preferred form of the invention, it being, however, understood that no limitation is necessarily made to the precise structural details herein exhibited, but the right is hereby reserved to any changes, alterations or modifications to which recourse may be had that come within the scope of the claims without departing from the spirit of the invention or sacrificing the efficiency of the same.

In the accompanying drawings:

Figure 1 is a perspective view of the improved rail chair, detached from the tie;

Fig. 2 is a detail sectional view of the device, illustrating the attachment of the same to the rail and tie;

Fig. 3 is a fragmental perspective view of the truss plate; and

Fig. 4 is a perspective view of one of the spring plates.

Referring to the figures by numerals of

reference, 10 designates the railway tie of ordinary wooden construction, but which may likewise be of metallic construction.

A base plate 11 is attached to the tie 10 by the spikes 12, which pass through the openings 13 at each end of the base plate.

The base plate 11 is of rectangular configuration and is preferably cast out of malleable steel of requisite toughness and said plate, adjacent its opposite ends, is formed with offsets 14 and 15, which latter are provided with angularly disposed channels 16 and 17.

Mounted on the base plate 11 and having its opposite ends 18 and 19 disposed in the channels 16 and 17 is the truss plate 20, constructed of spring steel metal. This plate 20 is formed with angularly disposed leg portions 21 and 22 which are joined at the central part by the flat horizontal portion 23. The flat horizontal portion 23 is formed with a seat 24 adapted for the reception of the base 25 of the rail 26. The leg portions 21 and 22, adjacent their connection with the flat portion 23, are formed with the bolt openings 27, and plates 28 and 29 are connected by bolts 30, to the upper ends of the angular leg portions 21 and 22. The bolts 30 pass through the openings in the plates 28 and 29, and the openings 27 in the truss plate 20, and nuts 31, when adjusted, hold the plates 28 and 29 in position thereon. The ends of plates 28 and 29 extend over the rail flanges 32 and preferably contact with the fish plates 33 and 34 which unite the confronting rail ends by means of the bolts 35 in the usual manner.

Attached to the base plate 11 at its central part by means of the bolts 36 are the spring plates 37, 38 and 39 which are formed with flat portions 40 and tapered upwardly inclined end portions 41 and 42, the extreme outer ends of which being bent over in tubular configuration as at 43. The lower spring plate 37 has its flat portion 40 engaging the upper surface of the base plate 11, and its tapered portions 41 and 42 are disposed at a moderate angle. The angle of the tapered portions 41 and 42 of the spring plate 38 is more abrupt than that of the tapered end portions of the spring plate 37 on the flat portion of which it is mounted. The spring plate 39 is nested

upon the plate 38 and has its tapered end portions 41 and 42 pitched at a more abrupt angle than that of the ends of plate 38.

The truss plate 20, on the under surface 5 of the inclined end portions 18 and 19 thereof, is provided with the spaced apart longitudinal ribs 44 and 45 which are apertured at 46. These ribs 44 and 45 are spaced apart at such distance to permit of the insertion 10 therebetween of the tubular ends 43 of the spring plates 37, 38 and 39.

Bolts 47 pass through openings 46 in the ribs 44 and 45 and likewise through the tubular end portions 43 of the spring plates 15 37, 38 and 39, by means of which they are connected to the truss plate 20.

In this manner, the spring plates 37, 38 and 39 are nested together on the base plate 20 11 by the bolts 36 and nuts 48, and their end portions have bearings upon the bolts 47 of the ribs 44 and 45 of the truss plate 20.

By positioning the truss plate 20 in such manner that its opposite ends 18 and 19, only project partly into the channels 14 of the 25 base plate 11, the same is capable of longitudinal adjustment due to the weight of the train and to the stress encountered. This adjustment and stress are regulated by the spring plates 37, 38 and 39, the inclined 30 ends 41 and 42 of which are adapted to be tensioned downwardly. The diminution of the angulation of the ends 41 and 42 of the spring plates varies in ratio to the weight of the train upon rails 26, and the stress 35 in consequence of the travel of the train thereover. The greater the stress encountered, the greater will be the reduction of the angularly disposed plate ends 41 and 42. As the upper spring plate 39 receives the 40 direct force of the weight and stress, its ends are pitched at a more abrupt angle than the

ends of plate 38 and consequently spring plate 38 has its ends pitched upwardly at a more abrupt angle than the ends of spring plate 37.

As the plate 20 is constructed of spring steel, the same is capable of limited resiliency, and the movement in longitudinal continuity of its ends 18 and 19 is limited in channels 16 and 17 in the offsets 14 of the 50 base plate 11.

It will thus be seen that the stress encountered by the rails will be imparted to the truss plate 20 and the spring plates 37, 38 and 39 and will thus be equalized.

Having thus fully described my invention, what I claim as new and desire to secure by Letters Patent is:

1. A rail chair comprising a base plate, said plate adapted for connection to a tie, 60 a truss member adjustably connected to the base plate, and a plurality of spring plates interposed between the truss member and base plate.

2. A rail chair comprising a base plate, 65 said plate adapted for connection to a tie, a truss member adjustably connected to the base plate, a plurality of spring plates interposed between the truss member and base plate, and means for connecting said spring 70 plates to said truss member.

3. A rail chair comprising a base plate, said plate adapted for connection to a tie, 75 a truss member adjustably connected to the base plate, a plurality of spring plates interposed between the truss member and base plate, and means for connecting the spring plates to said base plate and the truss member.

In witness whereof I have hereunto set my 80 hand.

NAZZARENO GIACOMELLI.
